(57) **CLAIM**

The ornamental design for a flocked swab, as shown and described.

DESCRIPTION

FIG. 1 is a perspective view of a flocked swab in accordance with the present design;

FIG. 2 is a side view thereof, the flocked swab having infinite order rotational symmetry about its center longitudinal axis so that all other side views are the same;

FIG. 3 is a bottom end view thereof; and,

FIG. 4 is a top end view thereof.

The broken lines shown in FIGS. 1 and 2 show portions of the flocked swab that form no part of the claimed design. The flocked swab is shown with a symbolic break in its length, indicated by the dash dot lines shown in FIGS. 1 and 2. The appearance of any portion of the article between the break lines forms no part of the claimed design.
